ELECTRICAL CONNECTION APPARATUS

Harry A. Douglas, Bronson, Mich., assignor to
 Kingston Products Corporation, a corporation
 of Indiana

Application May 31, 1935, Serial No. 24,256

5 Claims. (Cl. 173—328)

My invention relates to electrical connection apparatus, such as switches, sockets, and the like, and more particularly to electrical connection means which may be combined with and embodied in various forms of electrical connection apparatus. In the present embodiment of my invention the electrical connection means comprises a terminal post adapted for the reception of a plug conductor terminal of the snap type, and by embodiment of such an electrical connection means in electrical connection apparatus of various forms, the apparatus is adapted for use with plug conductor terminals of the snap type. The principal object of my invention is to provide new and improved electrical connection apparatus and means of the foregoing types. In the drawing accompanying this specification and forming a part of this application, I have shown for purposes of illustration, one form which my invention may assume, and in this drawing:

Figure 1 is a plan view of an electrical switch embodying my invention, the switch being fragmentarily shown.

Figure 2 is a perspective view of one of the terminal posts of the switch shown in Figure 1, the switch base and casing being shown fragmentarily.

Figure 3 is a longitudinal sectional view of a terminal post, taken along the line 3—3 of Figure 1, looking in the direction of the arrows, the base being fragmentarily shown, and a plug conductor terminal, cooperable with the terminal post, being added.

Figure 4 is a section on the line 4—4 of Figure 3, looking in the direction of the arrows.

Figure 5 is a section on the line 5—5 of Figure 4, looking in the direction of the arrows, and

Figure 6 is another perspective view of the terminal post, disassembled from the base, a portion of the base being fragmentarily shown, the view being taken looking in a direction toward the underside of the base and terminal post.

Referring to Figure 1 of the drawing the switch here shown includes an insulating base 11 closing the top of a casing 12, the casing being provided with fingers, the tips 13 of which are clinched over the top of the insulating base 11. The casing 12 is provided with a bracket 14, fragmentarily shown, whereby the casing may be suitably mounted. Within the switch casing 12 is disposed a movable switch member (not shown) operable by means of a reciprocable actuator 15, fragmentarily shown. The movable switch member is cooperable with contact studs, one of which 16

is shown in side elevation in Figure 3. Each contact stud, in this instance, is provided with a contact head 17 and has a shank 18 disposed through the insulating base 11. The contact head 17 may be seated in a recess 19 in the inside face of the base 11, and may project somewhat from the inside face of the base. The end 20 of the shank 18 may be spread laterally, as by riveting, swaging, or spinning, either over the upper surface of the insulating base 11, or over a conductor which 10 it is desired to electrically connect to the contact stud.

In this instance certain of the contact studs are electrically connected to and hold in position on the base a plurality of terminal posts 21 through 27, the number of posts depending on the nature of the switch and the desired circuit connections.

The terminal posts, 21 through 27 in the present embodiment, are all identical, and a description of the construction of one of them will serve for all.

Referring particularly to the terminal post 23 shown in Figures 2 through 6 this post comprises a tubular body portion 28 of generally oblong 25 rectangular cross-section, having narrower opposite walls 29, 30, and wider opposite walls 31, 32 at right angles to the narrower walls 29, 30. The upper (as viewed in Figure 2) wider wall 31 is made in halves, one half 33 being integral with 30 the left hand narrower wall 29 and the other half 34 being integral with the right hand narrower wall 30. The wall halves 33, 34 have their adjacent edges in abutment along a longitudinal line or plane of abutment 75. The lower wider wall 32 is also made in halves, one half 35 being integral with the left hand narrower wall 29 and the other half 36 being integral with the right hand narrower wall 30. The wall halves 35, 36 have their adjacent edges in abutment along a 40 longitudinal line or plane of abutment 76. The narrower walls 29, 30 are integrally joined at their tops by a loop 37 providing an aperture 38. The legs of the loop 37 are shown as having their margins 79, 80 tapering from the bight of the loop to the junction between the legs of the loop and the walls 29, 30. The upper ends of the wider walls 31, 32 may have arcuate margins 39, 40 conforming generally to the aperture 38 formed by the loop 37. The terms left, right, upper, lower and similar terms are used with particular reference to Figure 2, for convenience of description and are obviously merely relative terms.

The left hand wall half 35 of the lower wider 55

wall 32 is provided with a longitudinal extension 41, extending beyond the body portion 28 of the terminal post. The general plane of the longitudinal extension 41 is shown as parallel to but somewhat offset from the general plane of the wider wall 32, by an amount desirably equal to the thickness of the metal of the wall 32, and is integrally joined to the wall half 35 by an offset joint 42. The longitudinal extension 41 of the 10 left hand wall half 35 is wider than the wall half 35, and is here shown as approximately twice as wide as the wall half 35.

The right hand wall half 36 of the lower wider wall 32 is provided with a longitudinal extension 15 43 which is in the same general plane as the wall half 36 and is adapted to overlie the longitudinal extension 41 of the right hand wall half 35, in contact with the surface of the longitudinal extension 41.

20 The body portion of the terminal post 23 is provided with a transverse end wall 44, in this instance forming one leg of an angle piece having a leg 45 at right angles to the leg or wall 44. The transverse end wall 44 is of a width such that its opposite lateral margins may be respectively disposed between the opposite inside margins 46, 47 of the free ends of the narrower walls 29, 30. The longer leg 45 of the angle piece is adapted to overlie the longitudinal extension 43 of the right hand wall half 36. The longer leg 25 45 of the angle piece may be fastened in that position by providing the longitudinal extension 43 of the right hand wall half 36 with fingers 48, 49 adapted to be bent around a longitudinal 30 lateral edge 50 of the longer leg 45 of the angle piece and down against the upper surface of that leg. A longitudinal edge portion 77 of the extension 43, between the fingers 48, 49 is also bent in the same manner as the fingers 48, 49, except that edge portion 77 ends flush with the upper 35 surface of the leg 45. Also, the longitudinal extension 41 of the left hand wall half 35 may be provided with fingers 51, 52 which are long enough to be bent around a longitudinal lateral edge 53 of the longitudinal extension 43 on the right hand wall half 36 and a longitudinal edge 54 of the longer leg 45 of the angle piece, and down against the upper surface of the longer leg 45 of the angle piece. The longitudinal edge portion 78 of the extension 41, between the fingers 51, 52, is also bent in the same manner as the fingers 51, 52, except that that edge portion 78 ends flush with the upper surface of the leg 45.

50 The transverse wall 44 has its free end held in position by extensions 55, 56 on each of the wall halves 33, 34 of the wider wall 31, bent at right angles to the wall halves 33, 34 and against the outer surface of the transverse wall 44.

55 Detent means 57 is provided for cooperation with the aperture 38 formed by the loop 37. The detent means 57 here shown is of generally U-shape, the bight 58 being plane and provided at opposite margins with legs 59, 60. The bight 58 of the detent means 57 is provided with a protuberance 61, here shown as of semi-cylindrical form, the axis of the protuberance being at right angles to the axis of the aperture 38 formed by the loop 37. The protuberance 61 may be struck up from the material of the bight 58. The detent 60 means 57 is slidable within the tubular body 28 of the post and its movement toward the aperture 38 formed by the loop 37 is limited by shoulders 62, 63 formed by inward extensions on the narrower walls 29, 30, these shoulders 62, 63 being approximately at the tops of the walls 29, 30

where these walls merge with the ends of the loop 37.

The detent means 57 is biased in a direction toward the aperture 38 formed by the loop 37 by a helical spring 64, one end of which engages the 5 inside surface of the bight 58 of the detent means 57 and the other end of which engages the transverse wall 44.

For fastening the compound longitudinal extension, formed by the longitudinal extensions 10 41, 43 and the leg 45 of the angle piece, to a support, the two longitudinal extensions 41, 43 on the wall halves 35, 36 and the leg 45 of the angle piece may be provided with registering apertures 15 65, 66, 67 through which a fastening means is 20 adapted to pass. In order to prevent the terminal post 23 from rotating about a fastening means, the outermost longitudinal extension 41 may be provided with a projection 68 extending at right angles to the extension 41, here shown as struck 25 out from that extension 41, from the margin of the aperture 65. The projection 68 is adapted to fit in a notch or recess 69 extending radially from the margin of an aperture 70 in the base.

A contact stud, such as the contact stud 16, is 25 adapted to have its shank 18 disposed through the base aperture 70 and through the apertures 65, 66, 67 in the compound longitudinal extension and to have its end 20 spread over the outer surface of the leg 45 of the angle piece, thereby 30 tightly holding the terminal post 22 to the base 11.

In Figure 3 is shown a form of plug conductor terminal adapted to cooperate with the terminal post 23, the plug conductor terminal comprising in this instance a generally cylindrical portion 71 35 having an annular furrow 72 therein and a frusto-conical end 73. The plug terminal may be fastened to a conductor disposed therein by swaging, as indicated by swedge indentations 74. When the plug conductor terminal is inserted in 40 the aperture 38 formed by the loop 37, the frusto-conical end 73 acts against the protuberance 61 of the detent means 57 to move the detent means against the bias of the spring 64, continued inserting movement causing the protuberance 61 45 to snap into the annular furrow 72.

It will of course be evident that all of the terminal posts 21 through 27 shown in Figure 1 are adapted to receive plug conductor terminals, such as the one shown in Figure 3. It will further 50 be evident that whereas in the embodiment of Figure 1 the terminal posts are all mounted on a plane base, the axes of the plug terminal receiving apertures 38 of the posts are parallel and that the plug conductor terminals are easily insertable in the terminal posts irrespective of the angles which the longitudinal axes of the terminal posts 21 through 27 may make with each other. It will further be obvious that a plug conductor terminal may be inserted from either side 55 of any one of the terminal posts, where, as in the present embodiment, the terminal posts extend sufficiently over the edge of the support or base 60 on which they are mounted.

Considerable push or pull is required to insert 65 into or remove from a terminal post a plug conductor terminal of the snap type, as hereinbefore described. It will be apparent that the construction of the terminal post is designed to resist bending stresses, cause by such a push or pull, 70 or otherwise tending to bend the body portion of the terminal post with respect to the compound supporting extension.

It will be apparent that a terminal post, such as the post 23, may have its body portion 28, 75

the loop 38, the longitudinal extensions 41, 43, and the extensions 55, 56 made from a single integral sheet metal stamping, bent to the form hereinbefore described. The detent means 57 and the angle piece 44, 45 may obviously also be made of sheet metal.

From the foregoing it will be apparent to those skilled in the art that the illustrated embodiment of my invention provides new and improved electrical connection means and apparatus, readily and conveniently constructed and assembled, and accordingly, accomplishes at least the principal object of my invention. On the other hand, it also will be obvious to those skilled in the art that the illustrated embodiment of my invention may be variously changed and modified, or features thereof, singly or collectively, embodied in other combinations than those illustrated, without departing from the spirit of my invention, or sacrificing all of the advantages thereof, and that accordingly, the disclosure herein is illustrative only, and my invention is not limited thereto.

I claim:

1. Conductor terminal receiving means, comprising: a tubular body portion of generally rectangular cross-section, a pair of opposite walls adjacent one end thereof being extended and joined to form an aperture, the other end of said body portion being open, and a wall of said body portion adjacent said other end being provided with an extension having extending fastening means; detent means cooperable with said aperture and a plug conductor terminal receivable in said aperture; spring means to bias said detent means to operative position, said spring means and said detent means being disposed within said tubular body; and an independent transverse end wall for said body portion, substantially closing said other end, said end wall serving as an abutment for said spring means, and having a portion disposed adjacent said extension, and secured to said body portion by said extending fastening means formed on said extension.

2. Conductor terminal receiving means, comprising: a tubular body portion, a pair of opposite walls of which are extended and joined to form an aperture for receiving a conductor terminal, and the other pair of opposite walls being split, one of said other pair of split walls having ex-

tending portions generally overlying each other, and the opposite split wall having inwardly directed portions; and a separate member having a part in juxtaposition with respect to said overlying portions, and another part engaging said inwardly directed portions and closing off the adjacent end of said tubular body portion.

3. Conductor terminal receiving means, comprising: a tubular body portion, a pair of opposite walls of which are extended and joined to form an aperture for receiving a conductor terminal, and the other pair of opposite walls being split, one of said other pair of split walls having extending portions generally overlying each other, the extending portions, at opposite margins, being provided with inwardly turned fingers, and the opposite wall having inwardly directed portions; and a separate member having a part in juxtaposition with respect to said overlying portions and clinched thereto by said inwardly turned fingers, and another part engaging said inwardly directed portions and closing off the adjacent end of said tubular body portion.

4. Electrical connection means, comprising: an axially-split tubular sheet-metal body, the walls at one end of said body being extended and joined to form a loop for receiving a conductor terminal, and the walls on opposite sides of the split at the other end of said body being extended, the extended portions overlying each other; a support; and fastening means, engaging said overlying portions and said support, securing said body to said support, and holding said overlying portions against relative movement.

5. Electrical connection means, comprising: a tubular sheet-metal body of polygonal cross-section, opposing walls of said body being axially split, and opposing non-split walls being extended and joined to form a loop at one end of said body for receiving a conductor terminal, the walls adjacent one split being extended away from the other end of said body, the extended portions overlying each other; a support; and fastening means engaging said overlying portions and said support, securing said body to said support, and holding said overlying portions against relative movement.

HARRY A. DOUGLAS.
